(57) **CLAIM**

The ornamental design for a dispenser, as shown and described.

DESCRIPTION

FIG. 1 is a perspective view of a dispenser of the inventive design;

FIG. 2 is a front elevation view of the dispenser shown in FIG. 1;

FIG. 3 is a rear elevation view of the dispenser shown in FIG. 1;

FIG. 4 is a top plan view of the dispenser shown in FIG. 1;

FIG. 5 is a bottom plan view of the dispenser shown in FIG. 1;

FIG. 6 is left-side elevation view of the dispenser shown in FIG. 1; and,

FIG. 7 is right-side elevation view of the dispenser shown in FIG. 1.

The portions shown in stippled lines do not form part of the claimed design.

The dispenser is shown with symbolic breaks in its length and width. The appearance of any portion of the article between the break lines forms no part of the claimed design.
